GRINDING MACHINE

George W. Binns, Cincinnati, Ohio, assignor to
 Cincinnati Grinders Incorporated, Cincinnati,
 Ohio, a corporation of Ohio

Application June 7, 1932, Serial No. 615,863

20 Claims. (Cl. 51—129)

This invention relates to machine tools and especially to improvements in grinding machines.

An object of the invention is the provision of an automatic centerless grinder for grinding the 5 terminal portion of work pieces such as headed studs, tappets and the like.

Another object of the invention is the provision of improved means for actuating the said flat surfaces of the head or stud relative to the 10 grinding wheel while the work piece is being rotated.

A further object of the invention is the provision of improved feeding and ejecting means for properly positioning a work piece on a 15 support and ejecting it therefrom at the conclusion of the grinding operation.

Other objects and advantages of the present invention should be readily apparent by reference to the following specification considered in 20 conjunction with the accompanying drawings, forming a part thereof, and it is to be understood that any modifications may be made in the exact structural details there shown and described within the scope of the appended claims, without deviating from or exceeding the spirit of the invention.

In the drawings:

Figure 1 is a front elevation of a centerless grinding machine embodying the improvements 30 of this invention.

Figure 2 is a top plan view of the machine shown in Figure 1.

Figure 3 is a fragmentary longitudinal sectional view through the machine particularly illustrating the grinding throat as seen from line 3—3 on Figure 2.

Figure 4 is an enlarged fragmentary elevational view of the parts shown in Figure 3 which form the grinding throat.

Figure 5 is an enlarged transverse sectional view through the machine as seen from line 5—5 on Figure 2.

Figure 6 is an enlarged fragmentary elevational view of the parts as seen from line 6—6 on Figure 5.

Figure 7 is an end elevational view of the regulating or control wheel and parts associated therewith as seen from line 7—7 on Figure 3.

Figure 8 is an enlarged sectional view through the grinding wheel and nose of the grinding wheel spindle illustrating a mechanism whereby the said wheel is adjusted toward the work to take up for wear on the wheel.

Throughout the several views of the drawings

similar reference characters are employed to denote the same or similar parts.

A machine embodying this invention may comprise a bed 10 having formed on its upper surface a guideway 11 for a slide 12 which in turn is provided with a guideway 13 for a bracket or upper slide 14. The bed 10 has further rising therefrom at one side thereof a pedestal bearing 15 in which is journaled a spindle 16 for a grinding wheel 17. The upper slide or bracket 14 has secured to it a housing or head 18 in which is journaled a spindle 19 to the end of which is secured a wheel 20. The wheel 20, see Figure 3, is provided in its periphery with a notch 21 having on each side thereof vertical faces 22 and 23. From the point 24 of the face 23 the periphery 25 of the wheel gradually rises, which rise terminates at a point 26 from which the periphery 27 is substantially concentric with the axis of the spindle 19. This concentric periphery terminates at a point 28 where it joins the vertical face 22.

The grinding wheel 17 and regulating wheel 20 are respectively rotated at a high grinding rate of speed and a slow work controlling rate of speed, the former effecting the stock removal from the work, while the latter controls the rotation of the work and feeds same relative to the grinding wheel. The wheels are spaced from one another to form a work receiving throat in which the work piece is positioned. In order to support the work in the grinding throat, there is provided a work rest blade 29 having an inclined operative surface 30 which inclines in the direction of the periphery of the wheel 20. The work rest blade 29 is secured in a block 31 mounted on the end of a supplementary slide 32 which has formed on its under surface a dove-tailed guideway 33 receiving a correspondingly shaped tongue 34 formed on the upper surface of the lower slide 12. The block 31 has projecting from its forward face ears or lugs 35 through which passes a pivot pin 36 passing also through a bell crank lever 37. The lever 37 has rotatably mounted at one end of its one arm 38 a pressure roller 39 which is adapted to engage the work 40 and hold same against the periphery of the wheel 20. The other arm 41 of the bell crank 37 is likewise provided on its end with a roller 42 which co-operates with a cam carried by the wheel 20 for removing the pressure roller 39 from the work at the time a new work piece is to be positioned in the grinding throat.

In order to actuate the lever 37 about the axis of its pivot 36, the arm 41 has secured at 43 one end of a spring 44 which has its other end secured at 45 to the slide 32, and tends to oscillate the bell 55

crank in a clockwise direction or toward the wheel 20.

For positioning and adjusting the wheel 20 relative to the grinding wheel in accordance with the particular work piece being operated upon, the upper slide or bracket 14 has secured therein a nut 46 in threaded engagement with an adjusting screw 47 which has its rear end rotatably journaled in a bracket 48 carried by an extension 49 of the bed 10. Secured to the projecting portion of the screw 47 beyond the bracket 48 is a pilot or hand wheel 50 whereby the adjusting screw 47 is actuated. In order to shift the upper and lower slides 12 and 14 as a unit, relative to the bed 10, the upper slide carries a clamp 51 whereby they are fastened together. To independently adjust the slides relative to one another the lower slide 12 carries clamps 52 which upon release of clamp 51 secure the lower slide 12 to the bed so that the upper slide may be adjusted independently.

From the foregoing description of the wheel 20 it will be noted that the vertical face 23 shifts the work into position for engagement with the grinding wheel whereupon the eccentric portion 25 feeds the work relative to the wheel at the normal feeding speed until the concentric portion 27 is reached. At this time relative movement between the work and grinding wheel is held in abeyance to permit sparking out of the grinding wheel and work and to provide the desired finish on the work. Upon reaching the point 28 the vertical face 22 effects a rapid withdrawal of the work from the grinding wheel until it reaches the discharge notch 21 whereupon the work is carried from the machine and disposed in a suitable receptacle placed for its reception. In order to properly support the work on the work rest blade during its movement relative to the grinding wheel, the slide 32 is shifted simultaneously with the movement of the work. For this reason the slide 32 has pivoted to it by means of the pin 53 one end of a lever 54. This lever 54 is pivoted at 55 intermediate its ends to a lug or ear 56 projecting from the head or housing 18. An anti-friction roller 57 is rotatably carried by the upper end of the lever 54 and is adapted to be received in cam track 58 formed on the rear surface of the wheel 29. The cam track 58 bears a definite relation to the periphery of the wheel 20 so that as the said periphery shifts the work 40 toward the grinding wheel, it likewise shifts the slide 32 so that the blade 29 is at all times beneath the work and rotatably supporting it during the grinding operation.

In order to automatically feed the work pieces into the grinding throat, when the parts are substantially in the position shown in Figure 3, there is provided a hopper mechanism indicated in Figures 1 and 2 by the numeral 59. As seen in Figures 5, 6 and 7, the hopper mechanism terminates in a fixed guide or support 60 on which is slidably reciprocated a slide 61. The slide 61 is adapted to be shifted from the position shown in Figure 5 into the grinding throat and retracted therefrom once for each rotation of the wheel 20. This reciprocation of the slide 61 takes place during a very small portion of a single rotation of the wheel 20 and for which purpose suitable mechanism is mounted in the base of the hopper 59 and forming no part of this invention, it being sufficient that a work piece is inserted within the grinding throat after the finished work piece has been received in the discharge notch 21 and before the point 24 of the periphery of the wheel

comes into play. In order to position a work piece on the reciprocating slide 61 a ram head 62 is provided which disposes successive work pieces on the slide with one end thereof behind a shoulder 63 formed on the slide 61 which shoulder 63 acts as a pusher for the work as the slide is moved.

The work rest block 31, see Figure 6, has secured to its side an arm 64 rising upwardly above the work rest blade 29 and terminating in a head 65. A stripper latch 66 is pivoted at 67 to the head 65 of the arm 64 which stripper has connected to it one end of a spring 68, the other end being connected to the head 65. The spring 68 tends to oscillate the stripper in a clockwise direction or with its stripping point toward the work rest blade. A pin 70 projects from the head 65 to limit the clockwise oscillation of the stripper 66.

The operation of these parts is as follows: As the slide 61 moves forward with the rear end of the work piece butting the shoulder 63, the forward or head end of the work engages the stripper nose 69, which as will be noted in Figure 5, has a tapered side acting as a cam to raise the stripper nose above the head of the work as it is pushed into the grinding throat. As soon as the head passes beyond the nose 69 the spring 68 expands to return it to its normal position so that upon retracting movement of the slide 61, the nose 69 engages behind the head holding the work against retractive movement as the slide 61 is retracted. Continual retraction of the slide 61 permits the work to be dropped onto the inclined surface 30 of the blade 29. The parts are so timed that as the work drops onto the surface 30 the point 24 of the periphery of the wheel 20 is in position to prevent inadvertent discharge of the work from the blade through gravity.

As was noted above, the pressure roller 39 must be rendered inoperative during the loading of a new, unfinished work piece within the throat. For this reason the wheel 20 has secured thereto a segmental cam plate 71 having a rapidly rising cam surface 72 terminating in a track 73 concentric with the axis of the wheel 20. As the cam 72 engages the roller 42 the bell crank 37 is oscillated in a counter-clockwise direction about the axis of the pivot 36 for disposing the pressure roller 39 in the position shown in Figure 3. The roller is held in this position by the track 73 during the loading of the work.

In order that the new work piece be fed into the grinding throat at the time the parts are in the position to receive same, the wheel 20 has secured to its forward face a tripping cam 74 adapted to engage the nose 75 of a pivotally mounted crank 76 pivoted at 77 to a bracket 78 mounted on the upper surface of the slide 12. The other end of the crank 76 has pivoted to it 60 at 79 a link 80 which trips off the hopper actuating mechanism mounted within the base of the hopper above referred to.

The lower slide 32 has secured to its upper surface a bracket 81 by means of a bolt 82 and has 65 adjustably mounted in its upper end a stop member 83 here shown as a screw whereby the operative position of its nose 84 may be adjusted. A lock nut 85 is provided for securing the stop in adjusted positions and for holding same 70 against inadvertent movement. The nose 84 insures a definite stop against which the work piece is fed and held by means of the pressure roller 39. This roller, as shown in Figure 5, has its axis disposed at an angle or skewed to the axis 75

of the work 40 and tends to exert a feeding component on the work in the direction of the grinding wheel which is limited as above noted by the nose 84.

5 As is well known, grinding wheels are subject to wear and must periodically be trued to maintain a clean sharp face and must be adjusted to take up for this wear and truing. As shown in Figure 8, the grinding wheel 17 is carried by a collet 86 which is keyed as at 87 to a split sleeve 88. The sleeve 88 is in turn keyed at 89 to the tapered nose 90 of the grinding wheel spindle 16. The spindle nose 90 terminates in a reduced threaded portion 91 receiving a nut 92 which has its inner end butted against a shoulder formed by a counterbore in the sleeve 88. Actuation of the nut 92 toward the left, as seen in Figure 8, forces the sleeve 88 on to the tapered nose 90 and due to its split condition expands the said sleeve into close engagement with the collet 86. Therefore actuation of the nut 92 to the right will permit the sleeve 88 to be shifted off of the taper 90 to thereby permit a retraction of the sleeve so that the collet 86 may be axially adjusted relative thereto. To effect this axial adjustment of the collet 86 and grinding wheel 17 it has threaded therein a screw or stud 93 terminating in a head 94 received in a slot 95 formed in the sleeve 88. A screw driver slot 96 is formed in the head 94 so that the screw may be readily rotated. It is believed that the adjustment of the grinding wheel 17 relative to the spindle 16 will be readily appreciated from the foregoing description and by reference to Figure 8.

It should be noted that there has been provided a centerless grinding machine for grinding the flat surface of headed articles such as tappets and the like in an automatic, expeditious manner, which insures not only the proper finish on the work, but also that the work will be held within close limits of accuracy.

What is claimed is:

1. In a grinding machine for grinding the terminal portion of a cylindrical work piece the combination of a grinding wheel having an operative lateral or side face, a rotatable cam shaped friction control wheel laterally offset relative to the grinding wheel on the side of its operative lateral side face and having its operative surface so formed as to feed the work relative to the side face of the grinding wheel and present the entire terminal portion of the work to the grinding wheel during a single revolution of the friction control wheel, and a work support for peripherally supporting the work while in contact with the cam shaped friction control wheel and during the grinding of its terminal portion.

2. In a grinding machine for grinding the terminal portion of a cylindrical work piece the combination of a grinding wheel having an operative lateral or side face, a rotatable cam shaped friction control wheel laterally offset relative to the grinding wheel on the side of its operative lateral side face and having its operative surface so formed as to feed the work relative to the side face of the grinding wheel and present the entire terminal portion of the work to the grinding wheel during a single revolution of the friction control wheel, a work support for peripherally supporting the work while in contact with the cam shaped friction control wheel and during the grinding of its terminal portion, and means for holding the work on the work support

and in contact with the operative surface of the cam shaped regulating wheel.

3. In a grinding machine for grinding the terminal portion of a cylindrical work piece the combination of a grinding wheel having an operative lateral or side face, a rotatable cam shaped friction control wheel laterally offset relative to the grinding wheel on the side of its operative lateral side face and having its operative surface so formed as to feed the work relative to the side face of the grinding wheel and present the entire terminal portion of the work to the grinding wheel during a single revolution of the friction control wheel, a work support for peripherally supporting the work while in contact with the cam shaped friction control wheel and during the grinding of its terminal portion, means for holding the work on the work support and in contact with the operative surface of the cam shaped regulating wheel, and means for successively placing a work piece on the work supporting mechanism adjacent the face of the regulating wheel.

4. In a grinding machine for grinding the terminal portion of a cylindrical work piece the combination of a grinding wheel having an operative lateral or side face, a rotatable cam shaped friction control wheel laterally offset relative to the grinding wheel on the side of its operative lateral side face and having its operative surface so formed as to feed the work relative to the side face of the grinding wheel and present the entire terminal portion of the work to the grinding wheel during a single revolution of the friction control wheel, a work support for peripherally supporting the work while in contact with the cam shaped friction control wheel and during the grinding of its terminal portion, means for holding the work on the work support and in contact with the operative surface of the cam shaped regulating wheel, means for successively placing a work piece on the work supporting mechanism adjacent the face of the regulating wheel, and means synchronizing the operation of the last mentioned means with the rotation of the regulating wheel whereby a single work piece is disposed on the work supporting mechanism for each complete rotation of the friction control member.

5. In a centerless grinder for grinding the terminal portion of cylindrical articles the combination of a grinding wheel, an opposed control and feeding wheel, a work rest blade adjacent the periphery of the control and feeding wheel and forming between them a work receiving throat, means yieldably urging the work into contact with the control wheel while within the work receiving throat, means rendering the yielding holding means inoperative, and means feeding work pieces into the work receiving throat when the yielding means is inoperative.

6. In a centerless grinder of the class described the combination of a grinding wheel, an opposed control wheel, said wheels being operated respectively at a high grinding rate of speed and a relatively slow work controlling and feeding rate of speed, the control wheel having a cutaway portion, an eccentric feeding portion and a notched discharging portion, a work rest blade adjacent the periphery of the wheel for supporting a work piece while in peripheral engagement with the wheel, yieldable pressure means for holding the work in contact with the work rest blade and periphery of the control wheel, said pressure means exerting a feeding component on the work axially thereof toward the grinding wheel, and means for

limiting the movement of the work toward the grinding wheel.

7. In a centerless grinder of the class described the combination of a grinding wheel, an opposed control wheel, said wheels being operated respectively at a high grinding rate of speed and a relatively slow work controlling and feeding rate of speed, the control wheel having a cutaway portion, an eccentric feeding portion and a notched discharging portion, a work rest blade adjacent the periphery of the wheel for supporting a work piece while in peripheral engagement with the wheel, yieldable pressure means for holding the work in contact with the work rest blade and periphery of the control wheel, said pressure means exerting a feeding component on the work axially thereof toward the grinding wheel, means for limiting the movement of the work toward the grinding wheel, a feed slide shiftable into overlying relation with the work rest blade for placing a work piece on the blade, and means above the work rest blade for stripping the work from the slide upon retraction thereof.

8. In a centerless grinder of the class described the combination of a grinding wheel, an opposed control wheel, said wheels being operated respectively at a high grinding rate of speed and a relatively slow work controlling and feeding rate of speed, the control wheel having a cutaway portion, an eccentric feeding portion and a notched discharging portion, a work rest blade adjacent the periphery of the wheel for supporting a work piece while in peripheral engagement with the wheel, yieldable pressure means for holding the work in contact with the work rest blade and periphery of the control wheel, said pressure means exerting a feeding component on the work axially thereof toward the grinding wheel, means for limiting the movement of the work toward the grinding wheel, a feed slide shiftable into overlying relation with the work rest blade for placing a work piece on the blade, means above the work rest blade for stripping the work from the slide upon retraction thereof, and means retracting the pressure roll during the shifting of the slide into overlying relationship with the blade.

9. In a centerless grinder of the class described the combination of a grinding wheel, an opposed control wheel, said wheels being operated respectively at a high grinding rate of speed and a relatively slow work controlling and feeding rate of speed, the control wheel having a cutaway portion, an eccentric feeding portion and a notched discharging portion, a work rest blade adjacent the periphery of the wheel for supporting a work piece while in peripheral engagement with the wheel, yieldable pressure means for holding the work in contact with the work rest blade and periphery of the control wheel, said pressure roll exerting a feeding component on the work axially thereof toward the grinding wheel, means for limiting the movement of the work toward the grinding wheel, a feed slide shiftable into overlying relation with the work rest blade for placing a work piece on the blade, means above the work rest blade for stripping the work from the slide upon retraction thereof, means retracting the pressure roll during the shifting of the slide into overlying relationship with the blade, and means synchronizing the rotation of the control wheel with the retraction of the pressure roll and the shifting of the feed slide.

10. In a grinding machine of the class described for grinding cylindrical work pieces the combination of a grinding wheel, a work rest

blade for peripherally supporting a work piece, a carrier for the work rest blade mounted on the bed for movement relative thereto, a rotatable cam shaped control wheel for controlling the rotation of the work and feeding it relative to the grinding wheel to effect a stock removal therefrom, and means for shifting the work rest blade carrier toward the grinding wheel simultaneously with the shifting of the work relative to the grinding wheel to support the work during the grinding operation.

11. In a grinding machine of the class described for grinding cylindrical work pieces the combination of a grinding wheel, a work rest blade for peripherally supporting a work piece, a carrier for the work rest blade mounted on the bed for movement relative thereto, a rotatable cam shaped control wheel for controlling the rotation of the work and feeding it relative to the grinding wheel to effect a stock removal therefrom, and means for shifting the work rest blade carrier toward the grinding wheel simultaneously with the shifting of the work relative to the grinding wheel to support the work during the grinding operation, including a cam rotatable in timed relation with the rotation of the control wheel, and a link between the blade carrier and cam.

12. In a grinding machine of the class described for grinding cylindrical work pieces the combination of a grinding wheel, a work rest blade for peripherally supporting a work piece, a carrier for the work rest blade mounted on the bed for movement relative thereto, a rotatable cam shaped control wheel for controlling the rotation of the work and feeding it relative to the grinding wheel to effect a stock removal therefrom, means for shifting the work rest blade carrier toward the grinding wheel simultaneously with the shifting of the work relative to the grinding wheel to support the work during the grinding operation, including a cam rotatable in timed relation with the rotation of the control wheel, and a link between the blade carrier and cam, and a yieldably actuated pressure roll carried by the carrier for yieldably holding the work in contact with the work rest blade and the periphery of the control wheel during the shifting of the work while being operated upon.

13. In a grinding machine of the class described for grinding cylindrical work pieces the combination of a grinding wheel, a work rest blade for peripherally supporting a work piece, a carrier for the work rest blade mounted on the bed for movement relative thereto, a rotatable cam shaped control wheel for controlling the rotation of the work and feeding it relative to the grinding wheel to effect a stock removal therefrom, means for shifting the work rest blade carrier toward the grinding wheel simultaneously with the shifting of the work relative to the grinding wheel to support the work during the grinding operation, including a cam rotatable in timed relation with the rotation of the control wheel, and a link between the blade carrier and cam, a yieldably actuated pressure roll carried by the carrier for yieldably holding the work in contact with the work rest blade and the periphery of the control wheel during the shifting of the work while being operated upon, said pressure roll having its axis skewed as respects the axis of the work for feeding the work at an angle to the movement thereof as effected by the cam shaped control member and means for limiting said angular movement of the work.

14. In a grinding machine for grinding cylindrical work pieces the combination of a bed, a grinding wheel rotatably mounted on said bed, a work rest blade for supporting a work piece in operative relation to the grinding wheel, and a pair of cam shaped members, one for shifting the work relative to the grinding wheel to effect a stock removal therefrom and effect and control the rotation thereof and the second member for shifting the work support simultaneously with the shifting of the work relative to the wheel.

15. In a grinding machine for grinding cylindrical work pieces the combination of a bed, a grinding wheel rotatably mounted on said bed, a work rest blade for supporting a work piece in operative relation to the grinding wheel, a pair of cam shaped members, one for shifting the work relative to the grinding wheel to effect a stock removal therefrom and effect and control the rotation thereof and the second member for shifting the work support simultaneously with the shifting of the work relative to the wheel, and yieldable means for holding the work in contact with the work rest blade and said work feeding and rotation control cam member.

16. In a grinding machine for grinding cylindrical work pieces the combination of a bed, a grinding wheel rotatably mounted on said bed, a work rest blade for supporting a work piece in operative relation to the grinding wheel, a pair of cam shaped members, one for shifting the work relative to the grinding wheel to effect a stock removal therefrom and effect and control the rotation thereof and the second member for shifting the work support simultaneously with the shifting of the work relative to the wheel, yieldable means for holding the work in contact with the work rest blade and said work feeding and rotation control cam member, and means for intermittently supplying work pieces to the work rest blade.

17. In a grinding machine of the class described for grinding the terminal portion of a circular work piece the combination of a bed, a grinding wheel rotatably mounted thereon and having an operative side face, a work rest blade laterally spaced with respect thereto for movement transversely of the said lateral face, a rotatable friction control and feeding member in tandem relation with the blade, said friction control and feed member having a cam shaped peripheral surface for effecting said feed, and a cam member substantially co-axial with the friction control and feed member and rotatable in timed relation therewith for effecting the transverse movement of the blade relative to the wheel simultaneously with the shifting of the work.

18. In a grinding machine of the class described for grinding the terminal portion of a circular work piece the combination of a bed, a grinding wheel rotatably mounted thereon and

having an operative side face, a work rest blade laterally spaced with respect thereto, for movement transversely of the said lateral face, a rotatable friction control and feeding member in tandem relation with the blade, said friction control and feed member having a cam shaped peripheral surface for effecting said feed, a cam member substantially co-axial with the friction control and feed member and rotatable in timed relation therewith for effecting the transverse movement of the blade relative to the wheel simultaneously with the shifting of the work, and yieldably actuated means for holding the work in peripheral engagement with the work rest blade and rotation control member.

19. In a grinding machine of the class described for grinding the terminal portion of a circular work piece the combination of a bed, a grinding wheel rotatably mounted thereon and having an operative side face, a work rest blade laterally spaced with respect thereto for movement transversely of the said lateral face, a rotatable friction control and feeding member in tandem relation with the blade, said friction control and feed member having a cam shaped peripheral surface for effecting said feed, a cam member substantially co-axial with the friction control and feed member and rotatable in timed relation therewith for effecting the transverse movement of the blade relative to the wheel simultaneously with the shifting of the work, yieldably actuated means for holding the work in peripheral engagement with the work rest blade and rotation control member, and rotation control cam member.

20. In a grinding machine of the class described for grinding the terminal portion of a circular work piece the combination of a bed, a grinding wheel rotatably mounted thereon and having an operative side face, a work rest blade laterally spaced with respect thereto for movement transversely of the said lateral face, a rotatable friction control and feeding member in tandem relation with the blade, said friction control and feed member having a cam shaped peripheral surface for effecting said feed, a cam member substantially co-axial with the friction control and feed member and rotatable in timed relation therewith for effecting the transverse movement of the blade relative to the wheel simultaneously with the shifting of the work, yieldably actuated means for holding the work in peripheral engagement with the work rest blade and rotation control member, and means for intermittently supplying work pieces to the work rest blade.

GEORGE W. BINNS. 60
